UNITED STATES PATENT OFFICE

146,689

DESIGN FOR A PLASTIC FILM MATERIAL

Worthington Hamersley Southwick, New York,
N. Y., assignor to Samuel Levy, Brooklyn,
N. Y.

Application August 19, 1946, Serial No. 132,654

Term of patent 3½ years

(Cl. D92—1)

To all whom it may concern:

Be it known that I, Worthington Hamersley Southwick, a citizen of the United States, residing at New York city, in the county and State of New York, have invented a new, original, and ornamental Design for a Plastic Film Material, of which the following is a specification, reference being had to the accompanying drawing, forming a part thereof.

The figure is a plan view of a plastic film material, showing my new design. A complete design unit is outlined by the dot and dash lines, which unit is repeated over the material as indicated. Only one design unit is shown in full lines for convenience in illustration.

I claim:

The ornamental design for a plastic film material, substantially as shown and described.

WORTHINGTON HAMERSLEY SOUTHWICK.
